Primary Examiner — Sheryl Lane*Assistant Examiner* — Aula Soroush(74) *Attorney, Agent, or Firm* — Global IP Counselors, LLP(57) **CLAIM**

The ornamental design for a pet chew, as shown and described.

DESCRIPTION

FIG. 1 is a top perspective view of a first embodiment of a pet chew in accordance with our new design;

FIG. 2 is a bottom perspective view thereof;

FIG. 3 is a top view thereof;

FIG. 4 is a bottom view thereof;

FIG. 5 is an end view thereof; and,

FIG. 6 is a side view thereof.

The broken lines in the drawings illustrate portions of the pet chew that form no part of the claimed design.
